(57) **CLAIM**

The ornamental design for a ‘mounting bracket,’ as shown herein.

DESCRIPTION

FIG. 1 is a top perspective view of the mounting bracket when in an extended configuration;

FIG. 2 is an inverted view of one side of the mounting bracket when in an extended configuration;

FIG. 3 is a top plan view of the mounting bracket when in an extended configuration;

FIG. 4 is a view of the opposite side of the mounting bracket when in an extended configuration;

FIG. 5 is an underneath plan view of the mounting bracket when in an extended configuration;

FIG. 6 is a rear view of the mounting bracket when in an extended configuration;

FIG. 7 is a front view of the mounting bracket when in an extended configuration;

FIG. 8 is a top perspective view of the mounting bracket when in a collapsed configuration;

FIG. 9 is an inverted view of one side of the mounting bracket when in a collapsed configuration;

FIG. 10 is a top plan view of the mounting bracket when in a collapsed configuration;

FIG. 11 is a view of the opposite side of the mounting bracket when in a collapsed configuration;

FIG. 12 is an underneath plan view of the mounting bracket when in a collapsed configuration;

FIG. 13 is a rear view of the mounting bracket when in a collapsed configuration; and,

FIG. 14 is a front view of the mounting bracket when in a collapsed configuration.

The broken line showing of mounting structure is included for the purpose of illustrating environment and forms no part of the claimed design.
